TRAILER STABILIZING JACK

Robert B. Kearns, Shaker Heights, Ohio, assignor to
Production Experts, Inc., Cleveland, Ohio

Filed Mar. 20, 1972, Ser. No. 236,576

Term of patent 14 years

Int. Cl. D12—05

U.S. Cl. D41—1 D

FIG. 1 is an elevational view of one side of the trailer stabilizing jack, and

FIG. 2 is a top plan view thereof.

The opposite side of the jack is similar in appearance to FIG. 1.

I claim:

The ornamental design for a trailer stabilizing jack, substantially as shown and described.
